DESIGN FOR A RACK FOR SPICE CONTAINERS OR THE LIKE

Elizabeth Allen, Detroit, Mich.

Application September 6, 1940, Serial No. 94,833

Term of patent 3½ years

To all whom it may concern:

Be it known that I, Elizabeth Allen, a citizen of the United States, residing in Detroit, in the county of Wayne and State of Michigan, have invented a new, original, and ornamental Design for a Rack for Spice Containers or the like, of which the following is a specification, reference being had to the accompanying drawing, forming part thereof.

Fig. 1 is a front perspective view of a rack, for spice containers or the like, showing my new design;

Fig. 2 is a front elevational view of the same, taken at a point indicated by the arrow 2 in Fig. 1; and

Fig. 3 is an end elevational view taken at a point indicated by the arrow 3 in Fig. 1.

I claim:

The ornamental design for a rack for spice containers or the like, as shown.

ELIZABETH ALLEN.
